(57) **CLAIM**

The ornamental design for a goggle lens cover, as shown and described.

DESCRIPTION

FIG. 1 is a perspective view of a goggle lens cover showing my new design being applied to a goggle lens;

FIG. 2 is a front view of the goggle lens cover of FIG. 1 shown applied to a goggle lens;

FIG. 3 is a top view of the goggle lens cover of FIG. 1;

FIG. 4 is a bottom view of the goggle lens cover of FIG. 1;

FIG. 5 is a left side view of the goggle lens cover of FIG. 1; and,

FIG. 6 is a right side view of the goggle lens cover of FIG. 1. The broken lines shown in FIGS. 1-6 represent the portions of the design which form no part of the claim.
